CHILD'S PHONOGRAPH

Bernard Cohen, Brooklyn, N. Y.

Application March 26, 1953, Serial No. 24,208

Term of patent 3½ years

(Cl. D56—4)

To all whom it may concern:

Be it known that I, Bernard Cohen, a citizen of the United States, residing at Brooklyn, New York, in the county of Kings and State of New York, have invented a new, original, and ornamental Design for a Child's Phonograph, of which the following is a specification, reference being had to the accompanying drawing, forming part thereof.

In the drawing:

Fig. 1 is a front perspective view of a child's phonograph, showing my new design; and

Fig. 2 is a rear perspective view of the same.

I claim:

The ornamental design for a child's phonograph, as shown.

BERNARD COHEN.
